 corporation of Pennsylvania

Original application December 3, 1940, Serial
 No. 368,347. Divided and this application July
 24, 1941, Serial No. 403,797

3 Claims. (Cl. 219—37)

My invention relates to electric heaters, and more particularly to electric range units embodying one or more electrical resistance heating elements of desired types comprising a resistor disposed within and insulated from a metal sheath. The principal object of my invention is to provide new and improved electric heaters and new and improved electric range units of these types. This application is a division of my application Serial Number 368,347, filed December 3, 1940.

In the drawing accompanying this specification, and forming a part of this application, I have shown, for purposes of illustration, one form which my invention may assume, and in this drawing:

Figure 1 is a fragmentary plan view of an electric range unit illustrating an embodiment of the invention, parts being broken away to more clearly illustrate the construction.

Figure 2 is a fragmentary vertical sectional view corresponding substantially to the line 2—2 of Figure 1, showing the unit in position on the top of a stove,

Figure 3 is a fragmentary transverse sectional view corresponding substantially to the line 3—3 of Figure 2, and

Figure 4 is an enlarged transverse section corresponding substantially to the line 4—4 of Figure 1.

The embodiment disclosed in the drawing includes a range unit 110 which may comprise one or more heating elements, in this instance two elements 111, 112 of ring shape which are concentrically arranged. The elements 111, 112 are carried by spaced-apart supporting frames 113, the latter being secured to heat directing means, such as a reflector 114. The supporting frames 113 are detachably connected to an adaptor ring 115, which rests on a stove top 116, the reflector and some of the parts of the range unit 110 extending through an aperture 117 formed in the stove top.

The heating elements 111 and 112 are here shown as similar, each being of generally trapezoidal cross-sectional outline, and in this instance of isosceles trapezoidal outline. A detailed description of the member 111 is sufficient to describe both elements. Referring to Figure 4, the heating element 111 comprises a sheet-metal trough or channel 118 having side walls 119 and a generally plane wall 120 connecting the side walls 119. The side walls 119 are inclined so that each forms an obtuse angle with the connecting wall 120. Disposed within the channel 118 is electrical-insulating heat-conducting material 121 which may be in the form of suitable granular, comminuted or powdered refractory material, preferably compacted to a dense hard condition. If desired a bonding or cementing

material may be mixed with the refractory material.

An electrical-resistance heating means is embedded in the insulating material 121, and this heating means may assume various forms. As shown in the drawing, the heating means comprises five connected helical coils 122 of electrical resistance wire. The end coils, referring to Figure 4, are preferably dropped slightly below the plane of the intermediate coils, so that these end coils are properly spaced from the adjacent walls of the trough 118. A plate 123 is positioned within the trough 118 to overlie the insulating material 121, the plate 123 being generally parallel to the wall 120, and being of a width to extend substantially from one of the sides 119 to the other. The terminal portion of each side 119 is bent or crimped, as shown at 124 to overlie the plate 123, so as to hold this plate in assembled relation with the trough 118. As best seen in Figure 4, the plate 123 may be bowed in a direction inwardly of the trough 118, and the plate 123 and crimped portions 124 close off the open side of the trough.

In the embodiment herein shown, the heating element 112 is formed with inclined sides 125, a generally plane connecting wall 126, and a closure plate 127, the parts being substantially similar to the parts 119, 120, and 123, respectively, of the heating element 111. However, in this particular case, the heating element 112 is of a smaller transverse size than the heating element 111, and accommodates only three coils 128 of resistance wire, although it is entirely within the invention to change the size of the heating element 112, or of the heating element 111, or of both.

The method of forming the heating elements 111 and 112 comprises the provision of a sheet-metal channel or trough, such as the trough 118 hereinbefore referred to, having sides inclining away from each other in a direction toward the open end of the trough. As shown in dotted lines at 129, in Figure 4, the terminal portions of the sides are originally in an extended position to give unobstructed access to the interior of the trough. The refractory material and the heating means may be positioned within the trough in any suitable manner, one manner, for example, consisting of placing a certain amount of refractory material, in a granular, comminuted or powdered state, within the trough, and positioning the heating resistance in this material. If desired, a suitable bonding or cementing material may be mixed with the refractory material. The refractory material may be compacted to a degree wherein it retains its form, and then additional refractory may be added to overlie the material originally disposed within the trough. The entire mass of refractory material may then be compacted to a rather dense hard condition,

this compacting force being generally perpendicular to the wall 120 of the trough. The inclined sides 119 redirect this compacting force, so as to urge the refractory material to closely form about the coils 122, and also to closely form along the inside surfaces of the sides 119, the wall 120, and the bends forming the junctions therebetween. The plate 123 may then be positioned to overlie the refractory material, and the terminal portions of the sides 119 may be bent or crimped to overlie the plate 123. Preferably, the refractory material is so compacted as to have a concave outwardly directed surface, and the plate 123 is bent to concave form before being assembled with the trough 118. The concave form of the plate 123 tends to stiffen this plate, and therefore tends to maintain intimate contact between the inner surface of the plate and the adjacent surface of the refractory material.

Desirably, the heating element is subjected to a final pressing or squeezing action, to cause the walls of the trough and the plate to closely contact the refractory material, to highly densify the refractory material, and to close up any discontinuities or voids that may have been formed or left in the refractory material for any reason. This is particularly desirable where the heating element is designed so that the energy input is such that the element operates at elevated temperatures suitable for electric ranges. It is of course understood that the sheath of the element may be made of nickel, or a metal alloy, for example, nickel chrome, or "inconel," or of any material capable of withstanding such elevated temperatures or whatever temperature of operation may be selected. The final pressing or squeezing may be effected by placing the heating element in a die having a recess receiving at least part of the heating member, and pressing or squeezing the heating member by means of other suitable die means, such as by a die having a convex surface fitting the concave formation of the plate 123. In certain cases it may be desirable to effect the bowed formation of the plate 123 during the final pressing or squeezing formation.

In some instances, some or all of the steps of compacting the refractory material within the trough may be omitted, and this compacting may be effected when the plate 123 is assembled with the trough, or by the final squeezing or pressing action, or by both.

The plates 123 and 127 of the heating elements 111 and 112 are respectively formed with spaced-apart local depressions 130 and 131, each depression accommodating the head of a rivet 132, the rivet having a split shank passing through an aperture in the bottom of the depression. The depressions 130 and 131 are spaced in pairs along common radial lines, four pairs of depressions being provided in the embodiment shown.

Referring to Figures 2 and 3, the shanks of the rivets 132 also pass through apertures formed in generally inverted cup-shaped portions 134, 135 of the supporting frames 113, the latter corresponding in number to the four pairs of depressions, and washers 136 are positioned on the shanks of the rivets. The split ends of the rivets are bent to overlie the washers 136 and secure the heating elements 111 and 112 to the supporting frames 113. The cup-shaped portions 134 and 135 are integrally connected by legs 137, and the extremities of the legs 137 are formed with spaced-apart feet 138 which bear against one surface of the reflector 114, the ends of the

feet 138 passing through apertures 139 formed in the reflector 114 and being bent to overlie the opposite surface of the reflector 114.

Each of the supporting frames 113 has a finger 140, formed by bending toward each other portions of the cup 135 and adjacent parts of the legs 137. Each finger 140 is further formed with a hook portion 141 detachably latching with the margin of a respective one of a plurality of apertures 142 in a resiliently-distortable wall 143 of the adaptor ring 115. The wall 143 merges with a top wall 144, and this top wall in turn merges with a downwardly extending wall 145 the terminating margin of which is adapted to rest on the stove top 116 as shown in Figure 2.

The reflector 114 is provided with a curved lower edge 146 extending below the feet 138, and the reflector is inclined upwardly toward the center of the range unit, where it is provided with an aperture 147.

The heating elements 111 and 112 are provided with terminals 149 and 150, and certain of these terminals are connected by a connector strip 151, as shown in Figure 1, and these terminals lead 25 into a terminal box 152 formed to receive conductors leading from a suitable source of current supply.

Referring to Figure 2, the heating elements 111 and 112 are carried in side-by-side relation, that is, one side 119 of the heating element 111 is adjacent a side 125 of the heating element 112. In this relation the adjacent sides 119 and 125 incline away from each other, so that the distance between the sides is gradually increased in 35 a direction toward the top of the range unit 110, the inclination of the sides preferably being such that the normal lines of radiation from one surface do not strike the adjacent surface, thereby diminishing the inter-radiation between the inclined sides. It has been found that by the use of such heating elements greater efficiency is obtained, in that a greater amount of heat is conducted or radiated, or both, away from the elements in a useful direction. It is of course evident that when an object, such as a cooking vessel, is seated on the elements 111, 112, heat is adapted to be transmitted to the cooking vessel by direct conduction from the top walls 120, 126 and by radiation from the inclined walls 119, 125. 40 Also, under all circumstances of operation, because inter-radiation between the elements is materially reduced, the elements, at their adjacent surfaces, will not become overheated, and therefore the life of each heating element is greatly prolonged. Additionally, the inclined sides present a greater amount of surface radiating in a direction upward with reference to Figure 2, while at the same time the top wall, such as the wall 120 or 126, is actually reduced in width, 45 therefore diminishing the possibility of distortion or buckling of this wall.

It will of course be apparent that what has been hereinbefore stated with respect to reduced inter-radiation between adjacent portions 50 of two ring form elements such as the elements 111, 112, applies also with respect to adjacent portions of separate elements whether the longitudinal axes of the elements are circular, rectilinear, or any other form, and applies also with 55 respect to adjacent portions of a single element the longitudinal axis of which is such that the element has adjacent portions between which there might otherwise be substantial undesired inter-radiation.

By using heating elements of this type, rein-

forcing or embossing the top wall may be omitted if desired. The plate 123, because of its connection with the trough 118, and because of its particular shape, will assist in maintaining the sheath against any buckling action. Accordingly, the material at all times will closely encompass the refractory material, and thus materially assist in preventing cracks or discontinuities from forming in the refractory material.

The lower end of the wall 143 and the adjacent edge 146 of the directing member 114 define an annular port through which air or low velocity may enter, and becoming heated, flows in an upward direction, and escapes through the spaces between the element 112 and the wall 143, the elements 111 and 112, and between the element 111 and the top of the heat directing member 114. It will be appreciated that the frames 113 offer very little resistance to such flow of air, and the construction of this unit is such that transverse obstruction to the flow of air is materially diminished.

In some instances, it is preferable to provide the directing member 114 with a rather dull surface, instead of a bright reflecting surface. In such instances the air entering the annular port becomes heated to a greater extent by contact with the member 114, and flows with increased velocity toward the center of the unit, where it escapes, in somewhat chimney fashion, through the space between the element 111 and the upper part of the member 114, when no receptacle is positioned on the range unit 110. Additionally, air along the lower outer surface of the directing member 114 becomes heated, and flows upwardly through the central opening 147, thereby inducing an air flow through the annular air-inlet port formed by the lower end of the wall 143 and the adjacent edge 146 of the directing member 114.

It has been found that a range unit, designed in accordance with the foregoing, maintains a relatively low temperature when a receptacle and its contents are removed from the unit, therefore making unnecessary the extreme care ordinarily required to prevent "burning up" of the unit. Since the air-inlet port of the range unit is preferably below the top 116 of the stove, as shown in Figure 2, the flow of air into this inlet port induces movement of air along the bottom of the top 116, thereby preventing excessive heating of the stove top.

The radially positioned frames 113 are preferably stamped of sheet-metal, so that the overall weight of the unit is reduced. Also, the time required to heat up the unit is reduced, because the sheet-metal frames store very little heat. The frames 113 have been so constructed and arranged that air entering the annular port may flow over and in contact with the inner and outer surfaces of the legs 137, whereby additional heat is picked up by the air, and overheating of the frames is prevented.

It will be understood that the resistor may be made of any desired suitable material, and of any desired suitable form; that the refractory insulating material may be, or may include, for example, silica, or silicates, or magnesium oxide, or aluminum oxide, or any refractory oxide or combination of refractory oxides, or any other suitable refractory material, desirably of a mineral character; that such refractory material may

be mixed, if desired, with a bonding or cementing material, or mixed with a clay, or with any other suitable binder; that a sheath of desired suitable initial form, a resistor and insulating material may be assembled in any desired suitable way and in any desired suitable sequence; and that such assembly may be brought to final form in any desired suitable way.

From the foregoing it will be apparent to those skilled in the art that the illustrated embodiment of my invention provides new and improved electric heaters and new and improved electric range units, and accordingly, accomplishes the principal object of my invention. On the other hand, it also will be obvious to those skilled in the art that electric heaters and electric range units embodying my invention may be variously changed and modified, or features thereof, singly or collectively, embodied in electric heaters or electric range units or combinations other than those illustrated, all without departing from the spirit of my invention or sacrificing all of the advantages thereof, and that, accordingly, the disclosure herein is illustrative only, and my invention is not limited thereto.

I claim:

1. An electric heater, comprising: heating means; heat-directing means, underlying said heating means; and a plurality of spaced-apart sheet-metal elements, each comprising an inverted U-shaped part extending between and secured to said heating means and to said directing member, and holding said heating means and said directing means together as a unit, said heating means and said U-shaped parts being secured to each other by means including studs carried by said heating means and extending downwardly through apertures in the bights of the respective U-shaped parts.
2. An electric range or hot-plate unit comprising: heating means indicating an approximately flat annular plate; wall means circumstant said heating means; heat directing means disposed below said heating means and in spaced relation to said wall means and constructed and arranged to facilitate flow of air in through the space between said heat directing means and said wall and out through said heating means; and a plurality of spaced peripheral supporting means each connecting said heat directing means and said heating means and engaging said wall means, together supporting said heating means and said heat directing means from said wall means removable as a unit.
3. An electric range or hot-plate unit comprising: heating means indicating an approximately flat annular plate; wall means circumstant said heating means, supported from the top of the range or hot-plate; heat directing means disposed below said heating means and in spaced relation to said wall means and constructed and arranged to facilitate flow of air in through the space between said heat directing means and said wall and out through said heating means; and a plurality of spaced peripheral supporting means each connecting said heat directing means and said heating means and engaging said wall means, together supporting said heating means and said heat directing means from said wall means removable as a unit.
4. An electric range or hot-plate unit comprising: heating means indicating an approximately flat annular plate; wall means circumstant said heating means, supported from the top of the range or hot-plate; heat directing means disposed below said heating means and in spaced relation to said wall means and constructed and arranged to facilitate flow of air in through the space between said heat directing means and said wall and out through said heating means; and a plurality of spaced peripheral supporting means each connecting said heat directing means and said heating means and engaging said wall means, together supporting said heating means and said heat directing means from said wall means removable as a unit.

EDWIN L. WIEGAND.
